UNITED STATES PATENT OFFICE.

HARILAOS N. TZIMINADIS, OF NEW YORK, N. Y.

CRUDE-OIL-BURNING SYSTEM.

1,380,126.

Specification of Letters Patent. Patented May 31, 1921.

Application filed December 27, 1920. Serial No. 433,189.

To all whom it may concern:

Be it known that I, HARILAOS N. TZIMINADIS, a citizen of Greece, residing at New York city, in the county of New York and 5 State of New York, have invented certain new and useful Improvements in Crude-Oil-Burning Systems, of which the following is a specification.

This invention relates to crude oil burning systems.

It is a well understood fact that it is extremely difficult to burn the heavy crude oil as it flows from the wells without heating the same to a considerable degree.

One important object of the present invention is to provide an improved system for heating such crude oil in a highly economical and efficient manner.

It is also well understood that in the burning of crude oil it is necessary that the oil be atomized in some manner, as for instance by the use of steam or compressed air.

A second important object of the invention is the provision of an improved arrangement for generating the steam necessary to atomize the oil and at the same time for utilizing the heat of the steam to heat the oil in an improved manner.

A third object of the invention is the provision of an improved combined steam generator and oil heating tank for use in connection with systems of this character.

With the above and other objects in view the invention consists in general of a novel system employing certain unique combinations of elements and details of structure hereinafter fully described, illustrated in the accompanying drawings and specifically 40 claimed.

In the accompanying drawings, like characters of reference indicate like parts in the several views, and:

Figure 1 is a side elevation of a row of oven furnaces and showing the application of the invention thereto.

Fig. 2 is a partial section on the line 2—2 of Fig. 1, certain parts being shown in elevation.

Fig. 3 is a section on the line 3—3 of Fig. 2.

In the embodiment of the invention herein illustrated there has been disclosed the exterior wall 10 of an oven having for its bottom a series of furnaces arranged to be heated by suitable crude oil burners. These

furnaces each have a boardway 11 and a board 12 which parts may be of any preferred or desired construction. Adjacent this furnace is disclosed a skeleton tower 13 having a closed tank 14 on top thereof. This tank is provided adjacent its top and bottom with pipe fittings 15, these fittings being connected by a glass tube 16 constituting the oil gage. It is to be noted that each of the fittings 15 is provided with suitable stop-cocks so that in the event of the glass tube becoming clogged or broken the stop-cocks may be closed and a new tube substituted therefor. This tank 14 is what may 70 be termed the local storage tank, the main storage tank not being deemed necessary to be shown but from the main storage tank extends a pipe 17 which leads to a rotary pump 18 secured to the frame of the tower 75 and having connection by means of a pipe 19 with the top of the tank 14. Leading from the bottom of the tank 14 is a pipe 20 through which oil heated in the tank 14 may be drawn off for further heating if 80 desired. A drain pipe 21 is also connected to the bottom of the tank and is provided with a valve 22 for the purpose of controlling flow therethrough.

Considering now the steam generating 85 device it will be seen that a cylindrical drum or boiler 23 extends through the wall 10 and lies with its axis horizontal. Mounted on this drum or boiler is an oil heating tank 24 and the pipe 20 leads vertically upward through the outwardly projecting portion of the drum into the bottom of the heating tank 24 so that oil which flows through the pipe 20 will flow into this heating tank after passing through the hot water and steam in the boiler 23. It is also to be noted that by mounting the lower end of the tank 24 on the boiler 23 the oil in said tank receives heat directly from the upper part of this boiler. Extending upward from the boiler 23 and passing centrally through the tank 24 is a steam pipe 25 provided with a suitable valve 26 just outside the top of the boiler. The steam pipe 25 is also provided with a valve 27 95 spaced above the valve 26 for purposes which will be hereinafter set forth. The pipe 25 is continued and carried over to the top of the tank 14, passing downward through the top of said tank and connecting with a heating coil 28. The lower end of this heating coil has a connection with a

return steam pipe 29 passing into the side of the boiler 23 about opposite its axis. Leading from the pipe 25 is a branch pipe 30 which passes downward into the main supply tank 5 for the purpose of preliminarily heating the oil. This pipe 30 is controlled by a valve 31. Now by inspection of Fig. 1 it will be seen that if the valve 26 be opened steam will tend to flow through both the coil 28 and 10 the pipe 30. By closing the valve 27 all of the steam can be caused to flow through pipe 30. On the contrary, by closing the valve 31 and leaving the valve 27 open, all of the steam will flow through the coil 28. 15 In this manner flow of the steam may be regulated. A second branch pipe 32 also provided with a valve, as at 33, branches off of the pipe 25 between the valves 26 and 27 and may be connected for any desired purpose. 20 In the side wall 10 adjacent the boiler is an opening 34 normally closed by a suitable door 35 and supported just inside this opening is a crude oil burner 36 having its nozzle directed toward the boiler 23 so that 25 when this burner is lighted flame from the burner will strike against the boiler and cause the production of steam from the water therein. The burner 36 is connected by a pipe 37 having a valve 38 therein with the 30 tank 24. This burner is also connected by a pipe 39 with a chamber 40 formed on the outer end of the boiler 23, the pipe 39 being for the purpose of supplying steam to the burner whereby to atomize the fuel. A 35 feed pipe 41 serves to supply water to the boiler and is provided with the usual valve 42 for regulating such supply. Moreover, this pipe 41 has branches 43 and 44 each provided with a valve 45 whereby the flow 40 of steam through the pipes 43 and 44 to the steam side of crude oil burners 46 located in the furnaces may be controlled. Branching from the pipe 37 are oil supply 45 pipes 47 and 48 each having a valve 49 and these oil supply pipes like the steam pipes 43 and 44 lead to the crude oil burners 46, being connected to the oil side thereof. A sight gage 50 is located on the side of the tank 24 and one or more pressure gages 51 50 may also be located on this tank. It will be observed that the pipe 37 has its inner end extending downward close to the bottom of the oil tank and that the upper end of this oil tank is closed. By reason of the 55 tank 14 being at a greater height than the tank 24 the oil flowing down from the tank 14 will compress the air in the top of the tank 24 and this air pressure will be indicated on one of the gages 51. By properly 60 manipulating the valve 52 in the pipe 20 this pressure may be regulated. At the same time the air chamber not only assists in maintaining an even flow of oil from the tank 24 but also holds the oil flowing 65 through said tank in the bottom thereof to

obtain the advantage from its proximity to the boiler.

From the foregoing it will be seen that the oil, with this system, not only is heated in the main tank but is also heated in 70 the tank 14 and again in the tank 24 so that this crude oil is thoroughly heated and thus is rendered capable of easy atomization.

There has thus been provided a simple and efficient device of the kind described 75 and for the purpose specified.

It is obvious that minor changes may be made in the form and construction of the invention without departing from the material principles thereof. It is not, therefore, desired to confine the invention to the exact form herein shown and described, but it is wished to include all such as properly come within the scope claimed.

Having thus described the invention, what 85 is claimed as new, is:—

1. In a system of the class described, a furnace having a side wall, a cylindrical boiler projecting through said side wall, and an oil distributing tank mounted on the 90 boiler with the shell of the boiler forming the bottom of the tank.

2. In a system of the class described, a furnace having a side wall, a cylindrical boiler having one end projecting through 95 said side wall into the furnace, an oil burner within said furnace having its nozzle directed toward the inner part of the cylindrical boiler, an oil tank mounted on the outer part of the cylindrical boiler and having its bottom formed by the outer shell of said boiler, a valved steam pipe connection leading from the outer part of the boiler to the oil burner, and a valved oil pipe leading from said tank to said oil burner.

3. In a system of the class described, a furnace having a side wall, a steam boiler projecting through said side wall and having one end portion within the furnace and the other end portion projecting outwardly 100 therefrom, a vertical tank mounted on the outwardly projecting portion of the boiler and having its bottom formed by the boiler shell, the upper end of said tank being closed to form an oil chamber, a pipe connection from a source of oil supply passing upwardly through the boiler into said tank, and a draw-off pipe leading from the tank and terminating within said tank at a point adjacent the bottom thereof.

4. In a system of the class described, a furnace having a side wall, a steam boiler projecting through said side wall and having one end portion within the furnace and the other end portion projecting outwardly 115 therefrom, a vertical tank mounted on the outwardly projecting portion of the boiler and having its bottom formed by the boiler shell, the upper end of said tank being closed to form an oil chamber, a pipe con- 120

nection from a source of oil supply passing upwardly through the boiler into said tank, a draw-off pipe leading from the tank and terminating within said tank at a point adjacent the bottom thereof, an oil burner within said furnace and having its nozzle directed toward the inwardly projecting

portion of the boiler, a valved steam connection leading from the boiler to said burner, and a valved connection between the draw-off pipe and said burner.

In testimony whereof I affix my signature.

HARILAOS N. TZIMINADIS.
